UNITED STATES PATENT OFFICE.

AURION VILA CHEVERS, OF BOSTON, MASSACHUSETTS.

MUSICAL PIPE.

951,801.

Specification of Letters Patent. Patented Mar. 15, 1910.

Application filed March 29, 1909. Serial No. 486,484.

To all whom it may concern:

Be it known that I, AURION VILA CHEVERS, of Boston, in the county of Suffolk and State of Massachusetts, have invented 5 certain new and useful Improvements in Musical Pipes, of which the following is a specification.

This invention has for its object to produce a novel pipe, adapted for use as a 10 musical instrument and capable for adaptation to use as a tobacco pipe.

The invention consists in various features by which the functions above indicated are secured and by which the device is particularly and peculiarly adapted for the 15 ends sought.

My invention will be more fully described in the specification which follows and in the drawings which form a part thereof, in 20 which drawings I have shown embodiments of my invention illustrative of the principles thereof.

Throughout specification and drawing, like reference letters are used to indicate 25 corresponding parts, and in the drawings: Figure 1 is a side view of a pipe embodying my invention, adapted for smoking. Fig. 2 is a similar view partly in section. Fig. 3 is a view of a pipe having another form of 30 mouth-piece and adapted for use as a musical instrument. Fig. 4 is a view similar to Fig. 3, and showing a telescopic extension applied to the bowl of the pipe. Fig. 5 is a side view, showing the pipe adapted for 35 use as a musical instrument and provided with a mechanical air-supplying device. Fig. 6 shows a modification of the plug support shown in the preceding figures. Fig. 7 is a plan view of the pipe with a 40 bifurcated stem for two-users. Fig. 8 shows the pipe with an elongated flexible stem. Fig. 9 shows the pipe with a different mechanical air-supplying device. Fig. 10 shows a modification in the plug. Fig. 11 45 shows a modified form of the bowl.

B is a bowl open at both ends, but having a contracted opening C at the inner end, to one side of which a curved tubular stem A is joined, said stem being preferably made 50 round at its outer portion, and having a flattened end arranged at an angle to the bowl; so that a current of air issuing from the stem will flow across the opening C and cause a musical sound, when the plug hereinafter mentioned is not in place.

S is a mouth-piece such as is employed in smoking pipes.

F is a frame having clamping clips f adapted to embrace and slide on the curved stem A. The frame F is extended at G to 60 form a spring arm which supports a plug D, adapted to close the opening C when the pipe is used for smoking. The plug D is preferably recessed at d to form a cavity in which nicotin will be trapped, and provided 65 with an inclined opening or duct d' at its inner end which connects the interior of the bowl with the duct of the stem, when the plug is in place, as shown in Fig. 2.

X (Figs. 3, 4 and 11) is a terminal piece 70 on the stem, adapted for application to a nostril, and having a flange formed to bear on the margin of the nostril to form an air tight joint.

When used as a musical pipe, an extension composed of telescoping sections M, N, 75 may be applied to the bowl B for increasing the length of the column of air placed under vibration, so that the different tones may be produced by varying the length of the extension to produce a trombone effect.

When the device is used as a musical pipe, the air may be supplied by the lungs of the operator, the mouth-piece being applied to one of the nostrils, or by an air pump 85 connected with the stem by a flexible tube R, as indicated in Figs. 5 and 9.

In Fig. 5, H represents an elastic bulb which may be compressed to force air into a reservoir H' communicating with the tube 90 R. In Fig. 9, H² represents a bellows connected with the tube R. The mouth-piece S may be applied at one end of the flexible tube R, as shown in Fig. 8, so that the mouth-piece may be applied to a nostril of 95 the operator.

In Fig. 6 I have indicated a modified form of the plug support at G', said support being hinged to the stem A.

The stem may be bifurcated, as shown at 100 A' A' in Fig. 7, for the use of two operators.

The plug D may be engaged with the bowl B by other means than the frame F, and may be secured by friction, a screw thread 105 connection, or otherwise (see Fig. 10).

Although the instrument may be made of any suitable material, I find that it may be conventionally formed of metal, and I have indicated in Fig. 11 a construction of the 110

bowl which I find satisfactory. In this the bowl B, which is produced from a metal tube, is reduced or tapered at b', and has a stiffened dished flange b² to which the stem 5 A may be soldered.

When the device is used as a musical instrument, the plug D is opened, as shown in Figs. 3, 4, 5 and 8, 9, 11, and air is forced through the stem A from the lungs or from 10 a pump. This gives a whistling effect. The plug D being angularly disposed at the end of the pipe, acts as a deflector or resonator, modifying the normal sound of the instrument. To vary the sound of the instrument, 15 the plug D may be advanced toward the lower opening of the pipe by sliding the frame F longitudinally along the stem A.

When it is desired to use the device as a tobacco pipe, the plug D is closed over the 20 opening C, in which position the inner end of the stem A lies above the bottom of the cavity D. The pipe may be readily cleaned by removing the plug D.

A current of air, forced through the stem 25 A and passing across the opening C, produces a musical tone or whistle, the action being similar to that of a current of air blown across the mouth or neck of a bottle.

The tone may be controlled or varied to 30 produce any desired series of musical notes in playing a tune, by inserting the mouth of the bowl between the lips of the player, so that the bowl constitutes an extension of the vocal cavity, and forcing air through the 35 stem to operate the whistle. The player, by varying the form of vocal cavity, is enabled to vary the pitch of the musical tone produced, a range of two or more octaves being obtainable in this way. Air may be 40 forced through the stem by the lungs of the player, the stem being applied to one of the nostrils; or the air pressure may be produced by mechanical means such as those shown in Figs. 5 and 9, or by the lungs of an assistant, an elongated stem being employed, as shown in Fig. 8.

I claim:

1. A musical device, comprising a bowl 50 open at its outer end and having a contracted opening at its inner end, and a tubular stem secured to said inner end and terminating at one side of said opening, and arranged to direct a current of air across the said opening to produce a sound, the 55 bowl being adapted to form an extension of the vocal cavity of the operator's mouth, whereby musical notes may be produced.

2. A musical device, comprising a bowl 60 open at its outer end and having a contracted opening at its inner end, and a tubular stem secured to said inner end and terminating at one side of said opening, and arranged to direct a current of air across the said opening to produce a sound, the bowl 65 being adapted to form an extension of the

vocal cavity of the operator's mouth whereby musical notes may be produced, and the stem being provided with a flanged terminal piece adapted to bear on the nose of the operator.

70

3. A musical pipe, comprising a bowl open at its outer end and having a contracted opening at its inner end, a tubular stem secured to said inner end and terminating at one side of said opening, and arranged to direct a current of air across the 75 said opening to produce a sound, and a plug adapted to close said opening to adapt the pipe for smoking, the plug being provided with a duct connecting the duct of the stem 80 with the bowl when the plug is inserted.

4. A musical pipe, comprising a bowl open at its outer end and having a contracted opening at its inner end, a tubular stem secured to said inner end and terminating at one side of said opening, and arranged to direct a current of air across the 85 said opening to produce a sound, and a plug adapted to close said opening and having a flexible connection with the stem, whereby 90 the plug may be supported either in position to close said opening or at a distance therefrom, the plug being provided with a duct adapted to connect the duct of the stem with the bowl.

95

5. A device of the class described, comprising a tube having a contracted opening at its lower end, a tubular stem of relatively smaller diameter terminating adjacent to said contracted opening and angularly disposed thereto, and a plug mounted for angular adjustment to and from said opening adapted to close the same.

100

6. A device of the class described, comprising a bowl having a contracted opening 105 near its bottom, a curved tubular stem connected with the bottom of the bowl at one side of said opening, a curved support slidably engaging said stem, a plug on said support for closing said opening, and disposed substantially at right angles thereto, whereby said plug will be brought over said opening when the support is advanced toward the bowl, the plug being provided with a duct adapted to connect the duct of the stem 110 with the bowl.

115

7. A device of the class described, comprising a bowl, having a contracted opening in its bottom, a curved stem connected with the bottom of the bowl at one side of said 120 opening, a curved support slidably engaging said stem, a spring on said support, a plug on said spring for closing said opening and disposed substantially at right angles to said support, whereby the plug will be yieldingly applied to said opening when the support is advanced toward the bowl, the plug being provided with a duct adapted to connect the duct of the stem with the bowl.

125

8. A musical pipe of the class described, 130

consisting of a bowl open at one end and having a contracted opening at the other end, a tubular stem terminating at one side of said opening and having a flattened inner 5 end attached at an angle to the bowl, a detachable mouth-piece upon the outer end of the stem tube, a hollow plug movable relatively to said bowl to close the opening when the device is used as a smoking pipe, and adjust 10able at an angle below said opening to modify the tone when the device is used as a musical instrument, the plug being provided with a duct adapted to connect the duct of the stem with the bowl, substantially as described.

9. A device of the class described, com-

prising a bowl open at the outer end and having a contracted opening at the inner end, a tubular stem secured to said inner end and terminating at one side of said opening, and arranged to direct a current of air across said opening to produce a sound, and a telescopic extension detachably engaged with the open end of the bowl to modify the tones, whereby musical notes 20 25 may be produced, substantially as described.

In testimony whereof I have affixed my signature, in presence of two witnesses.
